UNITED STATES PATENT OFFICE.

CHARLES R. WHITTIER, OF NEW YORK, N. Y., ASSIGNOR OF ONE-HALF TO ERNEST W. MARSHALL, OF YONKERS, NEW YORK.

ACTUATING MECHANISM FOR ELEVATOR STOP DEVICES.

1,123,052.

Specification of Letters Patent. Patented Dec. 29, 1914.

Application filed January 24, 1912. Serial No. 673,228.

To all whom it may concern:

Be it known that I, CHARLES R. WHITTIER, a citizen of the United States of America, and a resident of the city, county, and State of New York, have invented certain new and useful Improvements in Actuating Mechanisms for Elevator Stop Devices, of which the following is a specification, reference being had to the accompanying drawings, forming a part thereof.

My invention relates to elevators and other apparatus having a moving car or member which is to be automatically brought to rest or the speed of which is to be changed automatically at a predetermined point or points in its travel, and it has special reference to means for actuating such stop or limiting devices as may be used for the purpose above indicated.

Elevators are usually provided with valves or limit switches depending on their character for automatically bringing the cars to rest when they reach the ends of their travel in either direction. Various means have heretofore been utilized for actuating these valves or switches at the proper time.

The object of my invention is to provide a relatively simple and durable mechanism for actuating such stop or limiting devices and to improve upon such arrangements as have heretofore been known.

By means of my invention the actuation of the stop or limit device may be not only controlled or governed to take place during the desired portion of the run of the elevator car or other member but also the rate at which the stop device is moved and the character of the movement produced may be adjusted to suit the conditions under which the apparatus with which it is used is intended to be operated.

Referring to the drawings:—Figure 1 is a diagrammatic elevation of certain parts of an elevator with my invention applied thereto. Fig. 2 is a view on a larger scale of a rope drum which in Fig. 1 is shown under the elevator car and carried by the car. Fig. 3 is a simple diagram of a slightly modified arrangement in which certain of the parts shown in Fig. 1 are duplicated. Fig. 4 is a longitudinal section of a

part of the rope drum, illustrating what I believe to be a particularly advantageous structural embodiment of my invention whereby the same drum may be set or adjusted to obtain various surface conditions. Figs. 5 and 6 are views corresponding to Fig. 2 showing modified drum structures. These figures are intended to illustrate the flexibility of my invention. Fig. 7 is a view of an arrangement which embodies my invention in another form and in which the ropes or cables which are depended upon for actuating the stop or limit device, move with the car. Fig. 8 illustrates still another modification of my invention in which the rope drum which controls the operation of the automatic stops floats in a rope or cable which is connected with an elevator car and with its counterweight and travels with them. Fig. 9 is a detail view in side elevation of the floating drum shown in Fig. 8. Fig. 10 shows another arrangement with a running rope with the stop actuating drum mounted on stationary bearings at the top of the elevator hatchway. The rope drum which is used in the arrangement illustrated in Fig. 10 is shown in side elevation in Fig. 11. Figs. 12, 13 and 14 illustrate different forms of rope drums which may be utilized in conjunction with the present invention and serve to still further illustrate the wide range of possible actions and effects which may be produced.

Like characters of reference designate corresponding parts in all of the figures.

Referring first to Figs. 1 and 2 of the drawings, the arrangement here shown comprises a car 10 having a counterweight 11 with which it is connected by rope or cable 12 which passes over a pulley or sheave 13 in the usual manner. The means for moving the car are not shown as they form no part of this invention.

On any part of the car, or other moving element is rotatably mounted a control drum 20. 14 is a rope cable or chain which runs from the top of the elevator hatchway to and around one part of this drum and 100 is affixed to it. The same or another rope or cable 15 is fastened to this drum and is wound around it and then led down to the bottom of the hatchway. Frictional con-

tact may be sufficient fastening if but one rope is used. To the lower end of rope 15 is affixed a weight 16, above which a connection is made between the rope and a stop device 17 at 18. As the stop device itself forms no part of my invention it is only shown diagrammatically.

The drum 20 comprises two sections 21 and 22 although these sections need not be constructed as separate pieces or with an intermediate flange. The control rope section 14 is wound onto the drum section 21 and the control rope section 15 is wound onto the drum section 22 in the same direction.

An automatic slack adjuster is shown in Fig. 1. This comprises a pulley or drum 23 and a ratchet wheel 24 which is operatively associated with the drum and a pawl or follower 25 which prevents rotation of the drum in one direction. The rope 14 is wound around this pulley or drum and to its end is attached a weight 26 which tends to keep the ropes 14 and 15 taut, since it acts in opposition to the weight 16 but is not sufficiently heavy to overhaul the latter.

Under the weight 16 is a fixed abutment 27 on which if the ropes 14, 15 stretch the weight will rest during the operation of the device as will appear more clearly presently. If any slack is in these ropes at such times, the weight 26 will take up the slack and the pawl 25 which co-operates with the ratchet wheel 24 will keep the tension in the rope constant. The rope section 14 is of course wrapped about the drum or pulley 23 a sufficient number of times to preclude the possibility of any relative movement between the rope and the surface of the drum.

The drum section 21 is not of plain cylindrical form throughout its entire length, as is clearly shown in Fig. 2, but is provided with enlargements 28 and 29 located near its respective ends. The drum section 22 as shown in this figure is cylindrical in form but this is not essential to my invention.

The number of turns of the rope sections 14 and 15 which are wrapped on the drum and the proportioning of the drum are such that one of the cables is being wound onto its drum section and the other cable is being unwound from the other drum section while the car is traveling in one direction, and vice versa.

The operation of the particular form of my invention which I have now pointed out is as follows: The main portion of drum section 21 is cylindrical and is of the same diameter as that of the drum section 22. Let us assume that the car is moving downward. The tension which this movement of the car puts upon rope 14 will rotate drum 20 to unwind rope 14, and this rotation will wind up rope 15 upon its part of the drum 65 at the same rate as that at which rope 14

is unwound. Consequently while these conditions prevail, the connection 18 with the stop device will remain stationary. But as the downward movement of the car continues the portion of rope 14 which is wound around the enlarged portion 29 will begin to be unwound.

On account of the increase in diameter of this part of the drum its rate of rotation, proportional to the rate of movement of the car, will be slower. Therefore the rope 15 will not be wound up as rapidly as it was or as rapidly as the car is descending. Consequently the point 18 will move downward and its connection with the stop device 17 will cause the latter to retard the movement of the car. The downward movement of the connecting point 18 will continue however until the car has been brought to rest. Then point 18 will have reached such position as that designated by *a* in Fig. 85 1. The enlargement 29 is proportioned to give the desired length and rate of movement of the stop device. It is therefore of a fixed size and shape. After enough of the cable 14 has been unwound from the part of the drum of enlarged diameter, its remaining convolutions will be found to be on a part 29^a of drum section 21 which part is of the same diameter as that of the drum section 22. Then even a continued movement 95 of the car will have no further effect upon the position of the connection 18. When the stop device has thus been moved to its extreme position, the weight 16 will be moved down to the abutment 27. If the cables 14 and 15 have stretched or for any other reason become loose, the weight 26 will take up this slack and the ratchet and pawl or equivalent mechanism will hold these ropes in their new positions. Thus 105 the ropes are maintained under desired tension and the proper adjustment of the connection point 18 is insured. Now when the car starts upward the operation of the parts described is reversed. The weight 16 causes the cable 15 to rotate drum 20 and to wind up rope 14. An upward movement of the car equal to the circumference of the part 29 of the drum will result in a complete rotation of the drum. This will unwind a part 110 of rope 15 equal to the circumference of the drum 22 and as this is less than the circumference of the part 29 and less than the travel of the car, the result is that the weight 16 is lifted. This will bring the connection 115 point 18 back to the position in which it is shown in full lines in Fig. 1 and will center the stop device. As the car approaches the upper limit of its travel, the rope 14 will begin to ride up upon the enlargement 28. This will cause more of the cable 14 to be wound up for each revolution so that the effective length of the cable sections 14, 15 120 will be shortened. Then the connection point 18 will be raised until it reaches the 130

position indicated at *b* in Fig. 1. The consequent movement of the stop device will arrest the travel of the car.

In connection with the foregoing description it may be noted that the movements of the stop device connection 18 may be made to begin at any desired parts of the car's travel.

It is often advantageous to set or adjust the parts to vary somewhat the relative positions of the car at which its movement causes the stop device to be actuated. In Fig. 4 a simple arrangement for making such adjustments is shown. In this figure 30 designates a cylindrical drum with a helical rope groove 31 cut in its outer surface. This corresponds with the drum-section 21 already described. 32-32 are collars having their inner surfaces threaded to fit the rope groove 31. If desired a clearance groove 33 may be also cut out of the inner surface of each of these collars. The outer surfaces of the collars may have any contour desired but they are preferably provided with rope grooves 34 which register with the rope groove 31. These collars may be turned in either direction to change their longitudinal positions on the drum, and when they have been set in the desired positions they may be held there by means of set screws 35. A plurality of threaded holes 36 are provided in the drum for the reception of these set screws. Obviously collars of different size or shape may be substituted for the collars 32. It is also to be noted that by properly proportioning the parts the movement of the connection 18 may be made at any desired rate proportional to the movement of the car, or in two or more distinct steps. The dotted line in Fig. 2 represents graphically the movement imparted to the connection 18 and to the stop device when the particular form of drum shown in Figs. 1 and 2 is used. In this figure the horizontal portion 37 represents the position of the point 18 during the intermediate parts of the car's run. As the car runs down, corresponding with a movement to the left of the cable 15 on drum section 22, the point 18 will begin to move downward as represented by the portion 38 of the dotted line. After it has been moved as far as desired it will again come to rest as represented by the part 39 of the dotted line. Obviously the movement of the stop device may be made as rapidly or as slowly as desired, or some parts of its movement may be made more rapidly than others, as its movement depends upon the relation between the parts of the controlling drum 20 with which the cable sections 14 and 15 contact at any given time.

By providing a second differential drum which is wound oppositely and another pair of cable section corresponding to the sec-

tions 14 and 15, the operating lever of the stop device may be positively actuated in both directions instead of allowing the weight 16 to actuate the lever in one direction as in the system of Fig. 1.

Referring particularly to the diagram of Fig. 3, a double ended lever 40 is substituted for the single lever of the stop device of Fig. 1. Rope sections 15^A and 15^B corresponding to the rope section 15 are connected respectively to the ends of the lever. Drums 41 and 42 which are wound oppositely are substituted for the drum 20, the enlarged parts being such that when the car reaches one limit of its travel there is a pull exerted from one of the cords as for example cord 15^A which turns the lever to position *a'* and when the car reaches the opposite limit of its travel the rope 15^B pulls the lever into position *b'*.

It is evident that the same effect may be produced by providing restricted portions such as 43 and 44 (see Fig. 5) in the drum section 22^A instead of providing enlargements 28 and 29 in the section 21. It is also possible to provide enlargements in one drum section and restricted portions in the other section or otherwise shape the surface of the drum to produce the desired action at the proper point in the operation of the elevator. Or a combination of two enlargements in one drum section and two restricted portions in the other drum section may be used if desired, as shown in the drum 20^B of Fig. 6.

The control rope may if desired be a running rope, *i. e.*, one which moves with the movement of the car. An illustration of an arrangement with two running ropes for actuating an elevator stop-device by means of a differential drum is shown in Fig. 7. In this case the stop-device has an arm 50 which is normally held in a horizontal position. At the ends of this arm are rope sheaves 52-53. 54 is a differential rope drum with suitable elevations and depressions in its cylindrical surface, which performs the same functions as the drum 20 of Figs. 1 and 2.

A rope or cable 55 is connected with the car, runs up over a guide sheave 56 to drum 54 about which it makes one or more convolutions, thence down to and under sheave 52 and back to the car. Another rope, chain or cable 57 runs up to and around drum 54 in the same direction, thence over guide sheave 58 and down to and under sheave 53 and back to the car. So long as the ropes 55 and 57 run over parts of drum 54 of like diameter which is the condition which remains while the car is passing over the intermediate parts of its path of travel, the position of the arm 50 will remain unchanged. But when the ropes run along to such portions of the drum that one of the

ropes is on a part of different diameter than is the other rope, the differential effect heretofore described will take place and the arm 50 will be tilted to one side or the other, according to the direction of movement of the car, to actuate the stop-device.

In Fig. 8 the car 10 and counterweight 11 connected by cable 12 which runs over a supporting sheave 13, are arranged as in Fig. 1. The stop-device 17 is shown at the bottom of the elevator shaft. But in this case its operating arm 60 is a forked lever near the end of which is rotatably supported a spirally grooved rope-drum 61. 62 is a rope, one end of which is connected with the car, which rope runs down to drum 61 around which it is given one or more turns and thence up to the counterweight to which its other end is affixed. The rope-drum then "floats" in a loop of the control rope or cable 62.

The movement of the car will cause the rope to move to the right or to the left of drum 61. Let us suppose the movement of the car causes the rope to move to the right as viewed in Fig. 9. It will after a time come to an enlarged portion 63 of the drum. Here a larger part of the rope will be wound upon the drum so that the effective length of the control rope will be shortened and the arm 60 will consequently be raised. On the other hand an opposite movement of the car will after awhile cause the control rope to move to the left until it reaches a restricted portion 64 of the drum. Here less of it will be wound up on the drum so that lever 60 will be lowered.

Another running rope arrangement is shown in Figs. 10 and 11, in which a section 65 of the control rope runs up to and is wrapped around a spirally grooved rope-drum 66 journaled at the top of the well. The central portion of this drum is cylindrical, and the end portion 67 is of enlarged diameter, and the other end 68 is of restricted diameter relative to the rest of the drum. The rope 65 makes one or more convolutions around the drum and is led down as at 69 and under a sheave 70 on a weighted arm 71 of the stop device and thence up to the car to which it is attached. During the intermediate parts of the car's run while the rope runs over the cylindrical part of the drum, the arm 71 will remain stationary. But as the car approaches its lower limit, for example, the rope 65 which in this direction of car travel is driving the drum 66, will run up onto the enlarged portion 67 and its effective length thereby shortened. This will cause the sheave 70 and arm 71 to be raised. When the car approaches the other end of its travel, the rope convolutions will run onto the restricted portion 68 of the drum to cause the stop device arm 71 to be lowered.

Fig. 12 shows a rope drum 72 of a different shape or contour than any of those hereinbefore described. Above the left-hand portion thereof is a dotted line 73 which illustrates graphically the character of mechanical movement which would be imparted to a desired element if a drum of this shape were used.

74 in Fig. 13 is still another form of drum and 75 its characteristic curve. 76 and 77 in Fig. 14 are another drum and its characteristic respectively. These figures have been added to show that from a given moving body almost any kind of a relative movement may be obtained by the use of differential drums or rope-drums having different diameters, as herein set forth. Even these are merely examples of what may be used for the drums may vary in character in infinite variety.

I have described several modifications of my invention to show that it is in no sense limited to any specific form or construction of parts. While I have described and shall claim this invention as applied to elevators, I do not mean to limit it to this one of its advantageous uses. The expression "actuated by the movement of the car" or similar expressions mean of course the movement of the car or some other moving part of the elevator which moves when the car does.

What I claim is:

1. The combination with a movable member and a stop device therefor, of a control rope connected with the stop device, a rope drum having varying diameters, and means for bringing the rope into operative relation with different parts of the drum during corresponding parts of the travel of said member, to thereby cause the movement of the member to actuate the stop device.

2. The combination with a movable member and a stop device therefor, of a control rope connected with the stop device, a rope-drum having a cylindrical portion and other parts of different diameters, and means for bringing the rope into operative relation with different parts of the drum, during corresponding parts of the travel of the movable member, said parts being arranged to cause the movement of said member to actuate the stop device when the control rope comes into relation to the parts of the drum of different diameters.

3. The combination with a movable member and a stop device therefor, of a control rope connected with the stop device, a rope-drum having a cylindrical portion and other parts of different diameters, means for bringing the rope into operative relation with different parts of the drum, during corresponding parts of the travel of said member, said parts being arranged to cause the movement of the member to actuate the stop device.

- device when the control rope comes into relation to the parts of the drum of different diameters, and means for adjusting the parts of the drum of different diameters, 5 relative to the cylindrical portion thereof.
4. The combination with a movable member and a stop device therefor, of a control rope connected with the stop device, a cylindrical rope drum having a helical groove 10 therein, an internally threaded collar with the threads thereof fitting the helical groove upon said drum, said collar having an irregular external surface provided with a helical groove registering with the helical groove 15 on the drum, means for bringing the rope into operative relation with the groove on the drum and with the groove on the collar during parts of the travel of said member, said collar being arranged to cause the 20 movement of the member to actuate the stop device when the control rope comes into relation with the groove on the collar.
5. The combination with a movable member and a stop device therefor, of a differential rope drum and a control rope connecting said stop device and rope drum, 25 said drum being arranged to act upon the rope to effect the actuation of the stop device.
- 30 6. The combination with a movable member and a stop device therefor, of a control rope connected with the stop device, a rope drum mounted on said member and having varying diameters, and means for bringing the rope into operative relation with different parts of the drum during corresponding parts of the travel of the member, to thereby cause the movement of said member to control the actuation of the stop device.
- 40 7. The combination with a movable member and a stop device therefor, of a control rope connected with the stop device, a rope drum loosely mounted on said member and having varying diameters, and means for 45 causing the movement of the member to bring said rope into operative relation with different parts of the drum during corresponding parts of the travel of the member, to thereby cause the movement of the member to control the actuation of the stop device.
- 50 8. The combination with a movable member and a stop device therefor, of a control rope connected with the stop device, a rope drum having varying diameters, means for bringing the rope into operative relation with different parts of the drum during corresponding parts of the travel of said member, to thereby cause the movement of the member to control the actuation of the stop device, and means for compensating for any stretch of the rope.
- 60 9. The combination with a movable member and a stop device therefor, of a control rope connected with the stop device, a rope 65
- drum having varying diameters, means for bringing the rope into operative relation with different parts of the drum during corresponding parts of the travel of said member, to thereby cause the movement of the member to actuate the stop device, and means for automatically maintaining the adjustment of the control rope.
- 70 10. The combination with a movable member and a stop device therefor, of a control rope connected with the stop device, and means comprising a rope drum having varying diameters coöperating with the control rope and actuated by the movement of said member to move the stop device a predetermined amount and thereafter remain unaffected by a further movement of the member.
- 75 11. The combination with a movable member and a stop device therefor, of a control rope connected with the stop device, means comprising a rope drum having varying diameters coöperating with the control rope and actuated by the movement of said member for actuating the stop device a predetermined amount but allowing the member to overrun without injury to the stop device.
- 80 12. The combination with a car and a stop device therefor, of a standing rope connected with a stop device, a movable rope drum having varying diameters, and means for bringing the rope into operative relation with different parts of the drum during corresponding parts of the travel of the car, to thereby cause the movement of the car to actuate the stop device.
- 85 13. The combination with a car and a stop device therefor, of a standing rope connected with a stop device, a rope drum having varying diameters, means for bringing the rope into operative relation with different parts of the drum during corresponding parts of the travel of the car, to thereby cause the movement of the car to actuate the stop device, means for limiting the movement of the standing rope in one direction, and means for automatically taking up any slack in said rope.
- 90 14. The combination with a car and a stop device therefor, of a differential rope drum, a standing rope connecting said drum and stop device, said drum coöperating with said rope to effect the actuation of the stop device, means for limiting the movement of the stop device in one direction, and means for automatically taking up any slack in said rope.
- 95 15. The combination with a car and a stop device therefor having a movable arm, of a standing rope connected to the movable arm of the stop device, a rope drum mounted on said car and having varying diameters, means for bringing the rope into operative relation with different parts of the drum during corresponding parts of the travel of

the car, to thereby cause the movement of the car to actuate said arm, means for limiting the movement of said arm in one direction, and means for automatically taking up 5 any slack in said standing rope.

16. The combination with a car and a stop device therefor, of a rope drum loosely mounted on the car and having varying diameters, a standing rope supported at the 10 upper end of the car's path of travel, wound about said drum and having a weight at its lower end, a connection between the stop device and said rope, the parts being so arranged that the movement of the car will rotate the drum to bring the 15 rope into operative relation with different parts of the drum during corresponding parts of the travel of the car, to thereby cause the movement of the car to actuate the stop device, 20 a fixed abutment for the weight, and a take up mechanism for keeping the rope taut and for maintaining the adjustment of the connection of the rope with the stop device.

17. The combination with a car and a stop 25 device therefor, of a cylindrical rope drum having a helical groove therein loosely mounted on the car, two internally threaded collars with the threads thereof fitting the

helical groove upon said drum, means for locking the position of said collars relative 30 to the drum, said collars having irregular external surfaces, each provided with a helical groove registering with the helical groove on the drum, a standing rope supported at the upper end of the car's path of 35 travel wound about said drum and having a weight at its lower end, a connection between the stop device and said rope, the parts being so arranged that the movement of the car will rotate the drum to bring the 40 rope into operative relation with different parts of the drum and with said collars during corresponding parts of the travel of the car to thereby cause the movement of the car to actuate the stop device, a fixed abutment 45 for the weight, and a take-up mechanism for keeping the rope taut and for maintaining the adjustment of the connection of the rope with the stop device.

In witness whereof I have hereunto set my hand this 23rd day of January 1912.

CHARLES R. WHITTIER.
